CLAIM

The ornamental design for a lid for containers for waste filters, as shown and described.

DESCRIPTION

FIG. 1 is an exploded front, top and side perspective view of the lid for containers for waste filters showing my new design;

FIG. 2 is a front elevational view thereof in the assembled condition, the rear being a mirror image of the front shown in FIG. 2;

FIG. 3 is a side elevational view thereof, the side opposite being a mirror image of the side shown in FIG. 3;

FIG. 4 is a top plan view thereof;

FIG. 5 is a bottom plan view thereof; and,

FIG. 6 is an exploded perspective view thereof.
